Phineas P. Quincy of Belfast. Maine.

Letters Patent.

The schedule referred to in these Letters Patent and making part of the same, containing a description in the words of the said Phineas P. Quincy, himself of his improvement in the construction of Locks for the fastening of Doors, Schedule Patented. 89.

To all persons to whom these presents shall come -

Be it known that I, Phineas P. Quincy of Belfast in the County of Waldo, 9 State of Maine have invented & made a new and useful improvement in the construction of Locks, for Doors, Chests, Drawers, &c. & the same have made constructed & applied to use, & which operates upon a principle heretofore unused and unknown, called the "Combination Screw Lock" specified in the words following, viz.

The Lock in addition to the case in which it is enclosed, & which may be in the shape of a door, chest, drawer, or cupboard, consists of a belt or bolt with two or more holes through it, through which two or more screws, are to pass, connected with slant holes in the belt so the two or more slots in the belt to receive the screws, at the places in the same screws which are grooved; also two or more screws, with one or more grooves in them to admit of their passing into the slots in the belt; the belt to contain a mortise or gap in which the key plays; the belt to be impaled with or without a spring, -- in order to place the belt in a situation to be moved, the screws must be raised or lowered until the groove in the screws come in a line with the slots in the belt; after the belt is moved a turn of the screws, either or all of them more or less, prevents the movement of the belt, until the screws are restored to the position in which they were before they were started. In the drawing, which is herewith transmitted the holes marked ab, are those through which the screws pass. The

190. 96778

hole marked C, is the key hole; B, the bolt. What I particularly and specifically claim as my own invention and for which I ask an exclusive right to use is - 1st. The constructing of locks either of wood or metal with bolts containing one or more holes or slits for the reception of screws with grooves in them; 2nd. The application of screws to said bolts in such way & manner, as to impede & prevent the movement of the bolt, in some positions & not to impede or prevent it in others, -----

In testimony that the above is a true specification of the improvement I have invented & claim a patent for, under the name of the "Combination screw Lock" as above named I have hereunto set my hand this thirty first day of March A.D. 1836
